EDWIN M. GOLDSMITH, OF PHILADELPHIA, PENNSYLVANIA, ASSIGNOR TO FRIED BERGER-AARON MANUFACTURING COMPANY, OF PHILADELPHIA, PENNSYLVANIA, A CORPORATION OF PENNSYLVANIA

BUTTONHOLE TAPE

Application filed September 27, 1930. Serial No. 484,856.

The object of the invention is to provide an improved button-hole tape. Such tape is used for a variety of purposes, among which may be cited the attachment of a severed length thereof, containing one or more button holes, to the end of an elastic tape, such as the suspender tape used for the suspension of brassières and corsets. My invention is particularly adapted for such use and in such application has advantages which will be hereinafter specified; although it will be understood that the improved button-hole tape is adapted for other uses and that the invention is not limited to any particular use.

5 A preferred embodiment of the invention is shown in the accompanying drawings, in which:—

Fig. 1 is a face view of a limited length of tape;

20 Fig. 2 is a face view of one severed repeat of the tape secured to the end of an elastic strap;

Fig. 3 is a diagrammatic edge view of Fig. 2; and

25 Fig. 4 is a face view of a modification of the tape of Fig. 1.

Tape embodying my invention is preferably, although not necessarily, of woven material with the warp extending longitudinally, and the weft transversely, of the fabric. The button-holes are preferably formed in the fabricating process, but they may less desirably be cut and worked in the fabric after it is made.

30 The tape comprises sections of single fabric *a* alternating with sections of double fabric *b*, *c*. It is preferred to make the fabric of two sets of warp threads, with both of which the weft threads interweave to form the sections *a*; while to form the sections *b*, *c*, one set of warp threads is interlaced with one or more weft threads to form a front ply *b* while the other set of warp threads is interlaced with the other weft thread or threads to form a rear ply *c*, the two plies being separate throughout their length and open along their side edges and being held in position only by their union with adjoining sections *a*. In this method of forming the tape, a section of single fabric *a* is of the same thickness as the

combined thicknesses of the front and rear plies, *b* and *c*, of a double section; but it will be understood that this construction and mode of fabrication of the alternating single and double fabric sections is merely preferred 55 and is not essential.

In each section, or in alternate sections, of single fabric are formed one or more button-holes *d* whose lengthwise extension is longitudinal of the tape. In securing all the objects of the invention two button-holes are formed in one section of single fabric, each button-hole being located fairly close to an adjacent section of double fabric but being spaced apart one from another a substantial 60 distance.

I have stated above that the button-holes are formed in each section or in alternate sections, of single fabric. The latter arrangement, and the one shown in Fig. 1 is 70 preferred. Each repeat of the specific tape shown comprises a relatively long button-hole section *a* of single fabric, and three relatively short sections, one, *b*, *c*, of double fabric, the next, *e*, of single fabric, and the next, 75 *b*, *c*, of double fabric. For the three short sections may be substituted one section of double fabric, as illustrated in Fig. 4. The two specified embodiments of the invention are adapted to the same use, but only the first 80 described embodiment exhibits all the advantages which it is desirable to secure. The way in which the tape is used, when applied to the purpose which I have mainly in view, will now be explained.

85 When it is desired to apply a length of button-hole tape to the end of an elastic suspension tape, the button-hole tape is cut across the lines *x*—*x*. This gives short tapes each having, at one end, two separate plies *b* and *c* united only at the adjacent transverse extremity of the section of single fabric *a* containing the button-holes *d*. At the other end of the short tape is a short section of single fabric *e*.

90 The ends of the two plies *b* and *c* are then bent inward upon themselves and one end of the elastic tape *f* is positioned between plies *b* and *c* and secured thereto by cross stitching *g*. This provides a very secure method of

fastening while avoiding a thick and unsightly bulge along the transverse line of union.

At the other end of the short tape, the fabric of the section *e* may be bent upon itself and stitched in position as shown at *h*. It is practicable, however, to omit, as above stated, the section *e*. In that case both lines of severance would be across sections of double fabric, and one of these sections would be, at the free end of the short tape, bent upon itself and sewed to form a closed end. Of course, the free end of the short tape may be merely hemmed across, or otherwise prevented from raveling.

What I claim is:—

A button-hole tape comprising repeats each of which comprises a relatively long section of single fabric having one or more button-holes and three relatively short sections which are successively of double fabric, single fabric and double fabric; each double fabric section comprising spaced apart parallel plies open along their longitudinal edges.

In testimony of which invention, I have hereunto set my hand, at Philadelphia, Pennsylvania, on this 25th day of September, 1930.

EDWIN M. GOLDSMITH.
